LENS SURFACING MACHINE

Gene G. Desiato, Rochester, N. Y.

Application July 13, 1956, Serial No. 597,667

11 Claims. (Cl. 51—124)

This invention relates to lens grinding and polishing machines, including machines for cylinder lens grinding and polishing, and spherical lens grinding and polishing.

The invention is directed to a lens surfacing machine of the character described wherein separate drives are provided for each of the upper and lower spindles of each of the pair of grinding units, and wherein a continuous flow of grinding or polishing compound is supplied to the grinding tools. The invention is further directed to a continuous common grinding or polishing compound supply and pump and pan arrangement embracing the grinding units, all of which can be quickly removed for thorough cleaning. Additionally the machine is so characterized that all bearings are completely protected from abrasives. The invention is further directed to a grinding unit capable of either lateral or angular adjustment, each adjustment being independent of the other. Further, the invention is directed to a machine which requires a minimum of attendance, and which may be time controlled, and which by reason of its construction, reduces substantially the time for grinding and polishing, as well as the consumption of abrasives used during the course of a day's operation.

The above and other novel features of the invention will appear more fully hereinafter from the following detailed description when taken in conjunction with the accompanying drawings. It is expressly understood that the drawings are employed for purposes of illustration only and are not designed as a definition of the limits of the invention, reference being had for this purpose to the appended claims.

In the drawings, wherein like reference characters indicate like parts:

Figure 1 is a front elevational view of the grinding apparatus with parts in section, and parts broken away;

Figure 2 is a sectional view through one of the mounts and through the pump, taken substantially on the broken line 2—2 of Figure 1;

Figure 3 is an elevational view of a tool support and pivotal guide members;

Figure 4 is a sectional view taken on the line 4—4 of Figure 3;

Figure 5 is a sectional view through the pump chamber taken on the line 5—5 of Figure 2;

Figure 6 is a fragmentary enlarged sectional view of Figure 2; and

Figure 7 is a circuit diagram.

As shown in Figures 1 and 2, the apparatus comprises a rigid hollow base 20 having a bottom plate 22, a deck plate 23 located thereabove, a front wall 24 and end walls 26 joining the bottom plate and deck plate, and a heavy back plate 28 extending above the deck, and forming a support for the upper spindle assemblies 30 and 32. Each of the spindle assemblies are alike and comprises a hollow spindle bearing bracket 34 overhanging the deck 23, such bracket having a support plate 36 pivotally mounted on a sector plate 38, which is in turn transversely

slidably mounted on the back plate 28 of the base. The pivotal mount of the plate 36 upon the sector plate comprises a shouldered bolt 39 extending through apertures in the plates 36 and 38, and through a transverse slot 5 in the back plate 28. The bolt is threaded into a block 42 having a threaded bore 44 through which extends a manual feed screw 46, one end of which is journaled in a central block 48, affixed to the back plate, and the other end of which is provided with a knob 51, and extends through an integral ear 52 on the block plate, a collar 50 being provided to prevent end play.

The sector plate is provided with rectangular raised portions 54 and 55 adapted to ride in transverse mating grooves 56 and 57 in the back plate 28 whereby the sector plate is held in vertical position at all times. A clamp bolt 58 and knob 60, threaded thereon, extends through a transverse slot 62 in the back plate, an aperture 64 in the sector plate and an arcuate slot 66 in the plate 36, such arcuate slot being concentric with the axis of the bolt 39. The sector plate is provided with worm teeth 68, which mesh with a worm 70 carried on a manually operated shaft 72 journaled in the flanges 74 of the support plate 36. By reason of the screw 46, and the worm 70, lateral and angular adjustment of the upper spindle 25 axis is readily effected, the one independent of the other, and when the desired setting of both is obtained, the lateral and angular adjustments are simultaneously locked by tightening the knob 60.

Each upper spindle bracket is provided with spaced bearings 73 and 75 in which is journaled a hollow shaft 76 having a step pulley 78 formed thereon. The pulley is driven by the motor 80, by the belt drive 82 as shown. The pulley hollow shaft or sleeve 76 is internally splined to receive the spindle 84, which spindle is splined as at 30 36 at its upper end and adapted to be moved axially within the pulley sleeve.

Slidably disposed in the bracket is a pressure sleeve 88 through which the spindle 84 extends. The sleeve has exterior rack teeth 90 engaging a pinion 92 mounted on a transverse shaft 94 adapted to be rotated manually by the lever 96. The sleeve has an enlarged bore portion 98 providing a shoulder 99 against which a thrust bearing 100 bears, such thrust bearing engaging the end of a coil pressure spring 102 surrounding the spindle. The lower end of such spring is seated in an internal shoulder 104 of a thimble sleeve 106 that is secured to the spindle by a cross pin 108. The sleeve 106 rotates with the bearing sleeve 110 disposed in the enlarged bore of the non-rotating pressure sleeve 88, and the lower end of such sleeve is provided with a seal bushing 112 provided with a seal 114, the inner face of which engages the exterior of the sleeve 106 in a running and sliding seal. The lower end of such sleeve is threaded to receive the yoke pin head 116 in which is adjustably mounted the crank offset 118.

It will be seen that the spindle and rack pressure sleeve 88 may be raised or lowered as a unit, subject to the spindle 84 and spindle thimble sleeve 106 having yielding movement against the spring 102 to apply yielding pressure between the work and the lap tool. A clamp bolt 120 with an arm 121 for securing the rack sleeve in any selected position is provided. Such bolt is threaded in a wedge flat sided sleeve 123, and extends through a second wedge flat sided sleeve 125, against which the bolt shoulder 127 bears.

Each spindle is independently driven by its respective motor.

Below each spindle is a lap or tool support or lower spindle 122 which forms an extension upon the output shaft 124 of a motor and gear reduction unit 126. A bearing bushing 128 provided with a seal 129 for the spindle

122 is secured to the deck. The upper end of the spindle is threaded as at 131 to receive the tool head 130. Each of the spindles 122 are independently driven by their respective motors 133 and 135, which as shown are mounted within the hollow base.

Centrally of the hollow base, and mounted on the bottom plate is a bearing sleeve 132 in which is journalled a vertical pump shaft 134, on spaced bearings 136 and 138. The upper end of such shaft is provided with a drive block 140 and impeller 142, the impeller hub and block having complementary projections and recesses 143 for effecting drive as well as the ready removal of the impeller.

A shallow pan 144, adapted to rest on the deck 23 is provided with upwardly flanged openings 146 for the bearing bushings 128, and has formed therein, an annular cup or reservoir 148 adapted to cooperate with the impeller 142. The cup is located in an aperture 25 in the deck 23. The cup has an annular central upwardly extending sleeve 145 extending up into the surrounding impeller skirt 147, and the impeller skirt is outwardly tapered to act as a slinger. The sleeve 145 is provided with an annular groove 149 to block any tendency for abrasive solution to escape over the upper edge thereof. The impeller has a plurality of radial blades 150 adapted to agitate the solution in the reservoir as well as to impel the solution centrifugally to cause discharge into the involute chamber 153 affixed to the rear side wall of the cup, whence the fluid flows up the outlet tube 164. The cup is provided with an annular shouldered recess 152 to receive an annular sloping removable drain ring 154, such ring has a ring seal 156, and forms a top closure for the cup and the impeller blades, and completes the impeller housing. The involute chamber of the pump housing has an outlet tube 164 which extends upwardly to a Y fitting 166 from which branch tubes 168 and 170 extend, such tubes having their discharge ends suitably formed to direct the discharge of abrasive solution upon the right rear side of each of the tools supported on the respective spindles 122. The tubes also loop over the work holder guide arms 200. The pump spindle is driven by a belt drive 172 from a motor 184 mounted on the back side of the back plate 28.

Each of the tool holders 130 are provided with a transverse rock shaft 188, journalled on anti-friction bearings 192, set in recesses 193 in the block 194. Pinned, as at 196 to the ends of the shaft, are sleeves 198 bearing arms 200, having lower diverging portions 202, and upper forked portions 204, to receive a work piece holder such as 206 having a lens 207 affixed thereto. The sleeves 198 project into the bearing recesses 193, and are provided with O ring seals 195. Pins 208 are provided to limit the angular movement of the arms 200, so that the upper ends of the arms cannot swing so far to one side or the other as to strike the feed tubes 168 and 170, which are so arched or formed as to clear the orbit of movement of the tips of the arms. The tool holders have a standard taper boss 210 with keying cross pin 212 to receive the lap tool 214. The tool holder has a deep skirt 216 adapted to overhang the pan flange 146, so as to provide protection against abrasive reaching the spindle 122 or its bearings.

A settable timer 220 having a control knob 221 is mounted on the front plate. The timer is adapted to close a circuit, and subsequently open the circuit after a predetermined time. The timer can be inserted in the power circuit 222 supplying the pump motor 184, the upper and lower spindle motors 133 and 80, and 135 and 81, as shown in Figure 7. Each pair of upper and lower spindle motors may be provided with switches 224 and 226 to break the connection to the return circuit 228.

It will be seen from the foregoing, that a machine is provided which is rigid in every respect, with the individual motors adding to the weight thereof to minimize the effect of vibration from the offset crank 118 on the work holder. Further the continual stirring and feeding

of the abrasive to the tools prevents danger of overheating during the grinding operation. The upper spindles are directly yielding against the pressure of the springs 102. In practice, fine grinding is accomplished in two minutes, and continual fine grinding uses but 9 tablespoons of emery in a seven hour day. Polishing is effected in 8 to 10 minutes and three tablespoons of serum oxide covers several days' production.

In practice, the machine will be set in operation for either grinding, or polishing, but whenever it is desired to change from one to the other, the pan can be quickly removed, by removing the tool holders, drain ring and pump impeller. Thereafter the pan is quickly flushed clean of the spent abrasive, so that change to another abrasive or fresh abrasive can be readily effected.

While tool holders with guide arms have been shown for cylinder grinding it will of course be appreciated that other tool holders known in the art may be employed. A feature of the machine is its ability to accept work rough ground on other machines, without being restricted to any one type of generator or lens body.

When the grinding or polishing operation is in progress, the slight orbital movement of the work holder 206 resulting from bringing the crank offset 118 down into operative engagement with the work holder crank recess, with such pressure as is desired, normally creates some vibration. However the weight of the drive motor affixed to each of the upper spindle brackets provides a rigidity coupled with inertia so as to provide freedom from vibration so as to result in precision operation. Further the compression spring 102, bearing as it does at its upper end upon the thrust bearing, provides a uniform pressure free of any extraneous axial vibration.

The angular adjustment of each head is effected without necessarily changing the lateral adjustment, and vice versa, and both adjustments are clamped simultaneously, at any set position. The spring pressure upon the offset crank is readily set by lowering the pressure sleeve 88 as desired, after which it is locked by the bolt 120.

By setting the timer to two minutes, for grinding or 10 minutes for polishing, assurance is had that when the job is completed, operation of the motors driving the upper and lower spindles will be stopped. The timer may be but a warning bell if desired.

Although a single embodiment of the invention has been illustrated and described, it is to be understood that the invention is not limited thereto. As various changes in the construction and arrangement may be made without departing from the spirit of the invention, as will be apparent to those skilled in the art, reference will be had to the appended claims for a definition of the limits of the invention.

What is claimed is:

1. In a lens surfacing machine, a base having a raised deck, a back plate extending upwardly from said base and above said deck, a sector plate mounted on said back plate above said deck, said plates having cooperating ways affording lateral relative movement, a spindle support plate pivotally mounted on a substantially horizontal axis upon said sector plate, said sector plate and support plate having a cooperating worm and worm wheel teeth for angularly moving said support plate relative to said sector plate, common locking means for securing said three plates rigidly together in any set position, a tool holding spindle mounted in said base and projecting upwardly through said deck, a work actuating spindle mounted on said spindle support plate above said tool spindle and forward of said back plate, and adapted for axial and angular alignment with said tool spindle and independent motors for driving said spindles, one of said motors being mounted in said base, and the other on said spindle support plate rearward of said back plate.

2. In a lens surfacing machine, a base having a raised deck with a central aperture therein, and a back plate extending above the deck, a pair of laterally spaced

lower tool carrying spindles projecting upward through the deck on opposite sides of said aperture, independent motor drive means for each of said spindles, upper work actuating spindles supported from said back plate located over said lower spindles, each of said work actuating spindles having a bearing support and having means laterally and angularly settable for mounting said support on said plate, independent motor drive means for each of said spindles mounted on each of said plates, a pan surrounding said tool spindles mounted on said deck, said pan having a central drain cup positioned in said deck aperture, a vertical pump impeller shaft journalled in said base and projecting upward through said aperture and cup, and having an impeller located in said cup, means for receiving centrifugal discharge of fluid abrasive draining into said cup, and for directing said fluid abrasive downwardly toward each of said tool carrying spindles, and an independent motor for driving said impeller shaft.

3. In a lens grinding machine, a base having an upstanding tool spindle, a bearing bracket mounted on said base in overhanging relationship to said tool spindle, an internally splined driving sleeve mounted in said bracket, a work actuating spindle having its upper end splined and projecting into said sleeve, a pressure sleeve slidably mounted in said bracket below said driving sleeve, and disposed around said spindle, a thrust bearing within the upper end of said sleeve, a coil spring disposed about and bearing downwardly on and rotating with said spindle, and bearing upwardly against said thrust bearing, and manual means for sliding said pressure sleeve in said bracket to lower said spindle.

4. In a lens grinding machine, a base having an upstanding tool spindle, a bearing bracket mounted on said base in overhanging relationship to said tool spindle, an internally splined driving sleeve mounted in said bracket, a work actuating spindle having its upper end splined and projecting into said sleeve, a pressure sleeve slidably mounted in said bracket below said driving sleeve, and disposed around said spindle, a thrust bearing within the upper end of said sleeve, a thimble sleeve secured at its lower end to said spindle and projecting upwardly along said spindle in spaced relation thereto, a coil spring disposed about said spindle and seated within said thimble and rotating with said spindle and thimble and bearing upwardly against said thrust bearing, and slideable and rotatable bearing means between said thimble and pressure sleeve, and means for sliding said pressure sleeve in said bracket to elevate or lower said spindle, and apply yielding axial pressure to said spindle through said spring.

5. In a lens grinding machine, a base having an upstanding tool spindle, an individual motor and drive mounted in said base for driving said tool spindle, a bearing bracket mounted on said base in overhanging relationship to said tool spindle, an internally splined driving sleeve mounted in said bracket, a work actuating spindle having its upper end splined and projecting into said sleeve, a drive motor having substantial inertia mounted rigidly on said bracket, and having means for driving said splined sleeve, a pressure sleeve slidably mounted in said bracket below said driving sleeve, and disposed around said spindle, a thrust bearing within the upper end of said sleeve, a coil spring disposed about and bearing downwardly on and rotating with said spindle, and bearing upwardly against said thrust bearing, and manual means for sliding said pressure sleeve in said bracket to lower said spindle.

6. In a lens surfacing machine, a base, a tool holding spindle projecting upwardly therefrom, a shallow pan surrounding the upper end of said tool holding spindle and having an aperture through which said spindle extends, said aperture having an upwardly extending circular flange concentric with the spindle, said pan having a sloping bottom and a circular cup depressed therein at a low point in the pan bottom laterally disposed from

said spindle, said cup having a central aperture and an upstanding annular collar surrounding the cup aperture, and said spindle having a depending circular flange disposed around said aperture flange, a vertical axis impeller disposed in said cup, said cup and impeller comprising a pump, a discharge duct leading from said cup to a point directed toward and located above said tool holding spindle, and a vertical drive shaft extending upwardly from below and through said cup aperture, said cup aperture having an upstanding surrounding collar, and said impeller having a depending surrounding skirt.

7. In a lens surfacing machine, a base having a raised deck with a central aperture therein, and a back plate extending above the deck, lower tool carrying spindles projecting upward through the deck on opposite sides of said aperture, upper work actuating spindles supported from said back plate located over said lower spindles, each of said work actuating spindles being laterally and angularly settable into or out of alignment with said lower spindles, a pan surrounding said tool spindles mounted on said deck, said pan having a central drain cup with a center aperture positioned in said deck aperture, and apertures having upstanding sleeves through which each of said lower tool spindles project, a cap 25 on each of said tool spindles, having a depending annular skirt surrounding the respective sleeves, a vertical pump impeller shaft journalled in said base and projecting upward through said aperture and cup, and having an impeller located in said cup, said impeller having a 30 depending annular skirt, and said cup center aperture having an annular upstanding collar extending upwardly within said impeller skirt, and means for receiving centrifugal discharge of fluid abrasive draining into said cup, and for directing said fluid abrasive downwardly toward 35 each of said tool carrying spindles.

8. In a lens surfacing machine, a base having a raised deck with a central aperture therein, and a back plate extending above the deck, lower tool carrying spindles projecting upward through the deck on opposite sides 40 of said aperture, upper work actuating spindles supported from said back plate forwardly thereof and located over said lower spindles, a laterally movable plate on said back plate for each upper spindle, an angularly movable plate mounted on said laterally movable plate for each 45 upper spindle, each of said tool carrying spindles being laterally and angularly settable and mounted on its respective angularly movable plate, a drive motor mounted on each angularly movable plate rearwardly of said back plate, and drive means for each motor and its upper spindle located above said angularly movable plate, a pan surrounding said tool spindles mounted on said deck, said pan having a central drain cup positioned in said deck aperture between adjacent lower spindles, a vertical pump impeller shaft journalled in said base and projecting upward through said aperture and cup, and having 55 an impeller located in said cup, means for centrifugally discharging fluid abrasive draining into said cup including a branched conduit for directing said fluid abrasive downwardly toward each of said tool carrying spindles, and independent motor means for driving each 60 of said spindles and said impeller shaft.

9. In a lens surfacing machine, a base having a raised deck with a central aperture therein, and a back plate extending above the deck, lower tool carrying spindles projecting upward through the deck on opposite sides 65 of said aperture, a tool holder on each of said spindles, said tool holders each having a transverse rock shaft and upwardly extending substantially parallel guide arms, and means for limiting the angular movement of said arms out of the vertical, upper work actuating spindles supported from said back plate and forwardly thereof and located over said lower spindles, a laterally movable plate on said back plate, an angularly movable plate mounted on said laterally movable plate, for each upper spindle, each of said work actuating spindles being later-

ally and angularly settable into and out of alignment with the respective lower spindles and mounted on its respective angularly movable plate, a drive motor mounted on each angularly movable plate rearwardly of said back plate, and drive means for each motor and its upper spindle located above said angularly movable plate, a pan surrounding said tool spindles mounted on said deck, said pan having a central drain cup positioned in said deck aperture between adjacent lower spindles, a vertical pump impeller shaft journaled in said base and projecting upward through said aperture and cup, and having an impeller located in said cup, and branch duct means for receiving the centrifugal discharge of fluid abrasive from said impeller draining into said cup, and for directing said fluid abrasive downwardly toward each of said tool carrying spindles, said duct means including a separate discharge tube for each tool holder extending over the path of movement of said arms, and terminating in a position extending below the upper ends of said arms and within the innermost orbit of movement of the upper ends of said arms.

10. A lens surfacing machine comprising a back plate, a sector plate mounted on said back plate, said plates having cooperating ways affording lateral relative movement, a spindle support plate pivotally mounted upon said sector plate, said sector plate and support plate having a cooperating worm and a worm wheel for angularly moving said support plate relative to said sector plate, common locking means for securing said three plates rigidly in any set position, a spindle bearing mounted on one side of said support plate, a drive motor mounted on the other side of said support plate, and belt drive means extending over the top of said support plate.

5 11. In a lens surfacing machine, a base having a raised deck, a back plate extending upwardly from said base and above said deck, a sector plate mounted on said back plate above said deck, said plates having cooperating ways affording lateral relative movement, a spindle support plate pivotally mounted on a substantially horizontal axis upon said sector plate, said sector plate and support plate having a cooperating worm and worm wheel teeth for angularly moving said support plate relative to said sector plate, common locking means for securing said three plates rigidly together in any set position, a tool holding spindle mounted in said base and projecting upwardly through said deck, a work actuating spindle mounted on said spindle support plate above said 10 tool spindle and forwardly of said back plate, and adapted for axial and angular alignment with said tool spindle, a drive motor mounted on said spindle support plate rearwardly thereof, and drive means between said motor and tool spindle located above said spindle support plate.
